APPARATUS FOR DISTILLING LIQUIDS

Filed July 23, 1923

UNITED STATES PATENT OFFICE

WALTER E. SANGER, OF CHICAGO, ILLINOIS; UNION TRUST COMPANY, OF DETROIT, MICHIGAN, EXECUTOR OF THE SAID WALTER E. SANGER, DECEASED, ASSIGNOR TO OSCAR H. WURSTER

APPARATUS FOR DISTILLING LIQUIDS

Application filed July 23, 1923. Serial No. 653,074.

This invention relates to an apparatus for distilling various liquids, and especially those which show a tendency to partially decompose directly or alone at normal pressure. Such liquids are distilled in a partial vacuum whereby the boiling point of the liquids is lowered in accordance with the degree of exhaustion. The improved apparatus is particularly adapted for distilling crude glycerine, but the invention is not limited to this particular substance.

The object of the invention is to provide an improved apparatus for performing distillations of the nature referred to above.

The present invention may be considered in some respects as an improvement upon the invention disclosed in my prior Patent No. 1,452,617, granted April 24, 1923.

The present invention is exemplified in the combination and arrangement of parts shown in the accompanying drawing and described in the following specification and in the steps of the process disclosed therein.

In the drawing, the figure is a diagrammatic elevation, with parts in section, showing one form of apparatus comprised in the present invention.

As shown in the drawing, the numeral 10 designates a still of the same general nature as shown in my prior patent referred to above. The still is provided with an internal heating coil 11 through which steam or other heating medium may be circulated for evaporating the contents of the still. The still may be additionally heated by an external source in the usual manner if desired. A pipe 12 enters the top of the still and is provided with a perforated spider 13 at the bottom from which heated vapor is discharged into the glycerine or other liquid within the still to assist in the operation. A ring or coil 14 is positioned near the bottom of the still and is of slightly less diameter than the coil 11. The ring is provided with perforations for directing fluid discharged therefrom toward the top of the coil 11. Outside the still the coil 14 is provided with connections 15 and 16 by which either air or steam may be introduced into the perforated ring 14. At the top of the still a second perforated ring 17 is

provided having openings through which water may be discharged over the coil 11 and a connection 18 is provided for supplying water to the perforated ring 17. A pipe 19 leads upwardly from the still 10 for conducting the vapors which pass through a trap 20 to a superheater condenser 21 in the manner described in my prior patent. A pipe 22 conducts the liquids which accumulate within the trap back to the still.

The condenser 21 comprises a central chamber 23 and end chambers 24 and 25 separated from one another by heads 26. The chambers 24 and 25 are connected by a series of tubes 27 passing through the central chamber 23. Baffle plates 28 are preferably provided for directing the vapor from the pipe 19 about the tubes 27. The tubes 27 are supplied with vapors at a lower temperature than that of the vapor from the still in a manner to be explained so that the vapor from the still will give up a portion of its heat to the vapor passing through the tubes and in this way a portion of the glycerine will be condensed and pass downwardly into a receiver 29.

The uncondensed portion of the vapor from the distilling liquid will rise through pipe 30 and pass through pipes 31 and 32 to a second condenser 33. To effect this operation the valve 34 will be closed and the valve 35 open. The condenser 33 is of the same general construction as a superheater condenser 21 and is provided with pipes through which a cooling medium may be circulated, the medium being supplied by connections 36. Water may be used as a cooling medium or oil may be employed and the amount of condensation may be controlled by the temperature of the cooling medium which can be regulated as desired.

The condensate from the condenser 33 passes through pipe 39 into a collector 40. If further condensation is desired the vapors may pass from the collector 40 through pipe 41 to a third condenser 42 similar to the condenser 33. Valve 43 will be closed and valve 44 will be open to secure this operation. The cooling medium is supplied to the condenser 42 by connections 45. The lower portion of the condenser 42 is connected by a pipe 46 to

100

a collector 47 and the upper portion of the collector 47 is connected by a pipe 48 to a suitable exhaust pump 49, by means of which the entire system is maintained at a reduced pressure. It will be readily seen that the higher the temperature of the condensing medium run through the various condensers, the less water vapor will be condensed with the glycerine, and glycerine of any desired 10 gravity may be obtained. For example, if a sufficiently high temperature condensing medium is used it would be possible to obtain glycerine of dynamite grade without further concentration. By the use of successive condensers with decreasing temperature of condensing medium all of the glycerine may be condensed separately, giving varying concentrations of glycerol. In some cases a single condenser 33 in addition to the superheater 20 condenser 21 will be sufficient, and in such cases the condenser 42 and its receiver 47 will be omitted.

The various receivers 29, 40 and 47 are arranged to drain into a pipe 50 which is connected by means of a pipe 51 to the bottom of a concentrator 52. The opposite end of the pipe 50 is connected through pipe 53 to the bottom of the evaporator 54, there being a syphon bend 55 in the pipe 53 for purposes 30 to be described. Valves 56, 57, 58 and 59 control the pipe connections so that the condensate from the different receivers may be conducted either to the concentrator 52 or the evaporator 54. The concentrator 52 is provided with a heating coil 60 which may be supplied with steam or other heating medium from any suitable source, and at the upper portion of the concentrator a separate coil or coils 61 is located to which a heating medium 35 may be supplied by connections 62' for superheating the vapor arising from the concentrator. The glycerine in the concentrator will have a relatively high boiling point so that the exhaust steam from the pipe 60 may 40 be used for supplying heating medium to the coil 62 in the evaporator 54. The evaporator 54 will be supplied either with water through a connection 63 or with the distillate from the receiver 47, or perhaps from the receiver 40. This distillate which enters the evaporator through pipe 53 will have the larger portion of its glycerine condensed therefrom and returned to the concentrator 52 through the pipe 51 so that the liquid supplied to the evaporator will have only a small 55 percentage of glycerine and is known as "sweet water."

The vapor from the evaporator 54 may be passed through pipe 65 to the upper portion 60 of the concentrator 52 where it is subjected to the action of the superheating coil 61 and mingles with the vapor from the concentrator 52. It then passes upwardly through pipes 66 and 67 to the superheater condenser 21 where under ordinary operation it is further

superheated by the vapors from the still and then passes through pipe 12 to the discharge head 13 at the bottom of the still where it is discharged into the crude glycerine to aid in distillation in the manner described in my prior patent. 70

It will be seen that the exhaust pump 49 operates through the various condensers in series to the top of the still 10. The upper portion of the evaporator 54 and concentrator 52 are connected with the bottom of the still so that the evaporator and concentrator will also operate at a reduced pressure due to the action of the pump, but in actual practice the pressure in the evaporator and concentrator will be greater than that in the still, the difference in pressure usually corresponding to a head of approximately ten inches of mercury. If the still is operated say under 28 inches of vacuum, the vapors from the evaporator are at a temperature of steam at approximately 18 inches of vacuum, or about 173° Fahrenheit. 80 85

The liquor in the concentrator is a highly concentrated solution of glycerine and water 90 with some impurities and has a boiling point of approximately 300° Fahrenheit and the vapors passing from the concentrator have a temperature closely approximating this temperature. I find that these vapors from a concentrated solution of glycerine (70 to 90% glycerol) will carry over mechanically or through partial pressure an appreciable amount of glycerol, these vapors after concentration of the same analyzing an average 95 of 3% of glycerine. Heretofore these condensed vapors have been collected as "sweet water" which yields an inferior product or were re-distilled with the "sweet water" if that method of disposing of glycerine in 100 "sweet water" was resorted to. In my improved process these vapors are not condensed directly but passed to the still in the form of vapors and are used for distilling the crude glycerine contained therein. With this 110 arrangement more glycerine is obtained in a purer form, such as dynamite glycerine. 115

I find that by providing superheating coils (through which there is passed steam at a temperature in excess of 360° Fahrenheit) 120 in the upper part of the concentrator and passing both the vapors from the evaporator and the concentrator around these coils, that the resultant mixture of these vapors enters the superheater at a considerably higher temperature than if the vapors of the "sweet water" evaporator are utilized and passed directly from this evaporator to the superheater condenser, as described in my prior patent referred to. With the vapors from the concentrator entering the superheater at a considerably higher temperature the efficiency of the injected vapors is increased and there is less steam required on the closed coil in the still and the crude glyc- 130

erine is distilled more rapidly. As the vapors enter the superheater at a higher temperature there is a smaller difference in temperature between the vapors passing from the still and the injection vapors so that less glycerine is automatically condensed in the superheater, and that which is condensed is of a higher degree of concentration.

By the use of successive condensers, as described with decreasing temperature of condensing medium, all of the glycerine may be condensed separately, giving various concentrations of glycerol in the different receivers. The piping of the return lines from the various receivers is so arranged that any part of the distillate may be returned to the concentrator or to the "sweet water" evaporator, as desired. As previously pointed out, the "sweet water" evaporator 54 will be under a vacuum of approximately 18 inches, while the "sweet water" receivers are more thoroughly exhausted and are under a vacuum of about 28 inches. In order that the "sweet water" will run by gravity from the receivers to the evaporator without danger of reverse flow it is necessary that there be a considerable difference in level or head between the bottom of the receivers and the level of the liquid in the evaporator. I find that by using a siphon 55 in the receiver return line, as shown in the drawing, less space is required between the bottoms of the receivers and the top of the evaporator, since it is always necessary to lift a head of water to the top of the siphon before there is danger of return flow from the evaporator to the receiver. This reduces the height necessary for the equipment, allowing it to be installed in buildings with lower ceilings. To further guard against any chance of return flow of the "sweet water" from the evaporator through the receiver and through the exhaust pump where it would be lost, a check valve 68 may be placed in the line 53 to prevent reverse flow therein. Since the same condition may exist in the connection between the concentrator and the receivers, a check valve 69 is also placed in the line 51.

In the distillation of crude glycerine the coils in the still become coated with material known as "foots" which is baked on the coil, thus interfering with the transfer of heat. This "foots" is readily soluble in hot water and by providing a perforated pipe 17 over the top of the heating coil and of substantially the same diameter as the heating coil, hot water may be run over the heating coil from this open pipe and the coil may thus be cleaned and kept in a high degree of efficiency. The same result may be obtained by running cold water through the perforated coil 17 and keeping a small amount of steam turned on on the closed coil in the still. I find further that by placing a perforated coil 14 in the bottom of the still hav-

ing connection for steam and air that a violent splashing may be obtained and the still may be thoroughly cleaned.

Assuming that, for instance, dynamite glycerine is to be produced, the crude glycerine is fed automatically into the still 10 to which external heat is preferably supplied. Air is now exhausted from the entire apparatus by means of the vacuum pump 49. The evaporator 54 contains water or is filled with "sweet water" from a previous distillation. This water is heated by the coil 62 and under the reduced pressure the "sweet water" in the evaporator passes out through pipe 65 into the concentrator 52 around the superheater coil 61 and into the superheater condenser 21. Here it passes through the tubes 27 and may be further superheated by the vapors of glycerine and steam which pass upwardly from the still through pipe 19 and pass around the condenser tubes 27. As the "sweet water" vapor which passes from the evaporator is saturated steam produced in a vacuum, its temperature is considerably below 212° Fahrenheit. The vapors passing from the liquid in the concentrator are produced under a vacuum, but due to the high concentration of glycerine therein they have a temperature considerably in excess of saturated steam at the reduced pressure, and also partly due to the fact that these vapors carry some glycerol and glycol. The vapors from the evaporator are heated by the vapors passing from the glycerine in the concentrator and the mixture of vapors from the evaporator and concentrator are both superheated by the superheater coil 61. Accordingly there may be a difference in temperature between the vapors from the still and the vapors passing from the concentrator, and the mixed vapors from the concentrator being cooler than those from the still may act as a condensing medium and a part of the glycerine will be condensed in the superheater condenser 21. The amount of glycerine so condensed is controlled by the amount of superheating done in the concentrator.

If the vapors from the concentrator are superheated to a temperature in excess of the temperature of the vapors from the still none of the vapors from the still will be condensed but on the contrary the vapors from the still will be superheated. If the vapors from the concentrator are superheated to a temperature below the temperature of the vapors from the still, some of the vapors from the still will be condensed and it will thus be possible to obtain pure glycerine in the receiver 29. The rate at which water vapors will be generated in the evaporator and mixed water and glycerine vapors will be generated in the concentrator will be controlled by the amount of evaporating surface provided in the evaporator and concentrator and the temperature which is there maintained. The

vapors which have been superheated in the concentrator 52 and in the condenser 21 pass downwardly into the still through pipe connection 12 and are distributed through the crude glycerine in the still by means of the perforations in the spider arms 13. The vapors thus injected cause the hot glycerine to distill over through the pipe 19, as stated. It will be noted that the pipe connection 12 extends downwardly through the still from the top thereof in the arrangement shown so that the steam contained in pipe 12 may be further superheated by the vapors of the distilling glycerine as they pass upwardly through the still on their way through the pipe 19. The part of the glycerine condensed in the condenser 21 drops into the receiver 29 from which it passes through pipe 51 into the concentrator 52. Most of the water vapor which is carried along with glycerine vapor does not condense in the superheater condenser, but passes along with the remaining uncondensed glycerine through pipes 30 and 32 to the condenser 33. If the condenser 33 is the only additional condenser employed, then the remaining vapor is condensed and drops into receiver 40 and from there passes through the pipe connections shown either to the concentrator 52 or the evaporator 54. If the additional condenser 42 is employed, the portion of the vapor not condensed in 33 is condensed in 42 and passes through the receiver 47 to the pipe connection 50, and thence to the concentrator or the "sweet water" evaporator where the glycerine is finally concentrated to a finished product.

Perforated pipes 70 and 71 are provided for injecting open steam into the lower part of the concentrator 52 and evaporator 54, respectively. If by any cause an impurity such as trimethylene-glycol is run into the concentrator with the glycerine, this substance may be distilled from the concentrated solution of the glycerine containing this impurity by injecting open steam through the perforated pipe 70 which is located below the level of the liquor in the concentrator. The open pipe 71 in the evaporator may be used in a similar manner.

In the distillation of chemically pure glycerine the process is the same as that described for distillation of dynamite glycerine, except that fresh water in place of "sweet water" is used for generating the vapor discharged at the bottom of the still. I find that in making a high grade of glycerine "sweet water" is unsuitable because some of the impurities of the "sweet water" are carried over into the still from where they are distilled over and collect partly in the concentrator making it impossible at times to secure a chemically pure grade to meet the requirements of the United States Pharmacopoeia. In carrying out the process with fresh water the water is supplied to the evaporator throughout the

period of distillation by means of the pipe connection 63 and no "sweet water" is used for generating water vapors. The water vapors from the fresh water pass around the superheating coil 61, but do not mix with vapors from the glycerine in the concentrator as the heating coil 60 in the concentrator not supplied with heating medium during the process of distillation and thus there are no glycerine vapors present. The "sweet water" which is condensed is held in the receivers until completion of distillation when they are evaporated in any suitable vessel.

It will, of course, be obvious that my process is not limited in its application to the distillation of glycerine, but that the same may be used in distilling other liquids which are distilled by steam or water vapors, and particularly such liquids which show a tendency to decompose when distilled at partial or normal pressure.

It will be apparent that the superheater coil 61 could be located in the evaporator 54 instead of concentrator 52. In this case the pipe 65 would connect with the concentrator at the top thereof and enter the evaporator below the superheater coil and the pipe 66 would lead the superheated vapors from the top of the evaporator 54 instead of from the concentrator, as illustrated. The two devices 52 and 54 are very similar in construction and operation and in fact either could be called an evaporator or a concentrator. The terms have been applied in the manner used above merely for convenience and because the vessel 52 is commonly supplied with a more concentrated solution of glycerine.

It should be noted that my invention is not limited strictly to the various details of the apparatus which has been particularly described, except as pointed out by the accompanying claims.

I claim:—

1. Distilling apparatus comprising a still, an evaporator, means for conducting vapor from said evaporator into the lower portion of said still, means for condensing vapors from said still, means for conducting the condensate of said vapors into said evaporator, means for closing conducting means to exclude said condensate from said evaporator, means for supplying fresh water to said evaporator so that said fresh water may be vaporized therein to produce fresh water vapors, and means for conveying said fresh water vapors to said still comprising a suitable conduit connecting said evaporator with said still.

2. In a distillation unit, the combination with a still of a "sweet water" evaporator, a "sweet water" receiver above said evaporator for receiving condensed vapor from said still, a conduit extending from said receiver to said evaporator, and a check valve in said

conduit preventing the return of the "sweet-water" to said receiver.

3. In combination, a still, a condenser for vapors from said still, a receiver for the condensate from said condenser, means for exhausting air from said receiver, a concentrator positioned below and having a conduit connection with said receiver, and a check valve in said conduit for preventing 10 return flow of liquid from said concentrator to said receiver under the influence of the vacuum in said receiver.

4. In distilling apparatus, the combination with a still, of a concentrator in the upper 15 part of which there is a superheating coil, means for condensing vapor from said still and directing the condensate to said concentrator, means separate from said superheating coil for heating the condensate in said 20 concentrator to dispel vapor therefrom, and a conduit opening into said concentrator above said superheating coil, said conduit being connected to said still to return said vapor to said still after it has passed said 25 superheater.

5. Distilling apparatus comprising a still, a condenser connected with said still, a concentrator, a liquid conduit through which condensate passes from said still to said concentrator, heating means associated with said concentrator, a vapor conduit connecting said concentrator and still through which vapor may be passed to said still, and a superheater for said vapors located near the top of said 35 concentrator.

6. In a distillation unit, the combination with a still, of an evaporator, a water line connected to said evaporator, a conduit connecting said evaporator with said still, and 40 means interposed in said conduit for heating the vapor from said evaporator before it enters said still.

7. In apparatus for distilling glycerine, the combination of a still, a condenser connected with the upper portion of the still, an evaporator arranged at a lower level than said condenser, means for exhausting air from said condenser, and a pipe line connecting said condenser with said evaporator arranged to permit gravity flow of condensate from the condenser to the evaporator, said pipe line having therein an upward bend constituting a siphon at the upper end adjacent the condenser, and means for independently heating the still and evaporator.

8. Distilling apparatus comprising a still, a series of condensers connected with said still for condensing vapor therefrom, a concentrator having a conduit connecting one of said condensers for receiving condensate therefrom, an evaporator having a conduit connecting another of said condensers for receiving the condensate in the form of "sweet-water" therefrom, and means for introducing

open steam near the bottom of said concentrator and of said evaporator.

9. Distilling apparatus comprising a still, means for introducing vapor into said still, a superheater condenser having a pair of conduits associated for heat exchange, one of said conduits being connected with said still for passing vapors to said still, the second of said conduits being connected with said still to receive the vapors therefrom, and means for superheating the vapor passing through said first-named conduit prior to its passage through said superheater condenser.

10. In apparatus for distilling liquids, the combination of a still, a condenser connected with the upper portion of said still, an evaporator arranged at a lower level than said condenser, means for exhausting air from said condenser, and a pipe line connecting said condenser with said evaporator arranged to permit gravity flow of condensate from the condenser to said evaporator, said pipe line having therein an upward bend constituting a siphon, and means for heating said still and evaporator.

11. In distilling apparatus the combination of a still, a series of condensers connected with the upper portion of said still, an evaporator arranged at a lower level than said condensers, means for exhausting air from said condensers, a pipe line connecting said condensers with said evaporator arranged to permit gravity flow of condensate from said condensers to said evaporator, said pipe line having therein an upward bend constituting a siphon, and means for heating said still and evaporator.

12. In distilling apparatus, the combination of a still, a condenser connected with the upper portion of said still, a receiver below said condenser, an evaporator arranged at a lower level than said receiver, means for exhausting air from said receiver, and a pipe line connecting said receiver with said evaporator arranged to permit gravity flow of condensate from said receiver to said evaporator, said pipe line having therein an upward bend constituting a siphon, and means for heating said still and evaporator.

In testimony whereof I have signed my name to this specification on this 18th day of July, A. D. 1923.

WALTER E. SANGER.
